UNITED STATES PATENT OFFICE.

HENRY D. STRONG, OF CHICAGO, ILLINOIS.

JAR-CLOSURE.

No. 831,810.

Specification of Letters Patent.

Patented Sept. 18, 1906.

Application filed January 8, 1906. Serial No. 294,620.

To all whom it may concern:

Be it known that I, HENRY D. STRONG, a resident of Chicago, in the county of Cook and State of Illinois, have invented certain new and useful Improvements in Jar-Closures, of which the following is a full, clear, and exact description.

The invention relates to jar-closures, and more particularly to that type commonly known as "vacuum-jars."

The invention designs to provide a jar-closure which can be conveniently used in the household and in which the seal is formed by paraffin or like material which will be caused to flow between the cap and the jar and into the mouth of the jar as the material in the jar contracts and the temperature thereof is lowered.

The invention further designs to provide an improved jar-seal.

With these objects in view the invention consists in the several novel features herein-after set forth, and more particularly defined by claims at the conclusion hereof.

In the drawings, Figure 1 is a section of a jar embodying the invention and showing the paraffin sealing material as it is applied and before a vacuum or partial vacuum is formed in the jar. Fig. 2 is a similar view showing the jar when the seal has been formed as the result of the contraction of the material in the jar. Fig. 3 is a plan view.

a denotes the body of a jar or can, which may be of any suitable material, usually of glass. The upper end of the jar is provided with a neck *b*, which is smaller in diameter than the body of the jar, and an outer flange *c*. A channel or groove *d* is formed between the neck *b* and the flange *c* for the reception of the paraffin sealing material, and a flange or rim *e* of a cover *e* extends into said channel. The inner periphery of the cover-flange is somewhat larger than the outer periphery of the neck *b*, thus leaving a space therebetween for the sealing material. The bottom of the channel *d* is slightly tapered, as at *d'*, to centralize or properly position the cover in the channel. A spout *g* may be provided, if desired, for directing the paraffin into channel *d*. The cover *e* is provided with a rib *e'*, by which the cover can be raised by a prying-tool of suitable sort. This rib is preferably omitted at one point to provide as large a space as possible for the introduction of the paraffin into chamber *d*. The neck of the jar is at least as high as flange *c* to prevent

any excess of paraffin overflowing into the jar.

When a jar is to be closed, the channel *d* is filled with melted paraffin or like material, the cover having first been placed on top of the jar, which is done while the material in the jar is hot. The jar and contents are then allowed to cool, which causes the material in the jar to contract, forming a partial vacuum therein, which causes the paraffin in channel *d* to be drawn upwardly between the jar-neck and the cover-flange, over the neck, and into the mouth of the jar. As a result a wafer or body *i* of paraffin is provided in the neck of the jar, which forms an effective inner seal for the contents of the jar, and the paraffin also forms a seal between the cover and the jar at *k*. When the paraffin is cool, the wafer will form an air-tight seal for the mouth of the jar. The cover will protect the wafer-seal, and the paraffin between the cover and the neck will also form an effective seal between the jar and cover and hold the cover in tight relation with respect to the jar. The preponderating air-pressure on the top and the paraffin when set are ample to secure the cover in place to protect the inner seal.

It will be observed that the channel *d* is of sufficient size and so formed as to contain paraffin in sufficient quantity to not only fill the space between the cover and the jar-neck, but also sufficient to form the wafer-seal in the neck of the jar. Manifestly when the jar is formed of glass there is an accurate fit between the bottom of the cover-flange and the jar, so that the paraffin will be drawn into the jar. When the jar-cover is to be removed, it is only necessary to insert a knife or other prying-tool beneath the rib *f*, which will break the seal between the cover and the jar, and thereupon the cover can be readily removed. It will be understood that the cover-flange does not fit snugly around the neck of the jar, so that breakage in prying the cover will be avoided.

The sealing material employed is that commonly known as "paraffin." It will be understood, however, that other equivalents may be used. A viscid fluid, such as that commonly known as "sealing-wax," which becomes solid when set, is not suitable in the practice of the invention. Another characteristic of the closure is that the paraffin sealing material passes into the jar and remains between the outer periphery of the jar-neck and the inner periphery of the cover-flange.

Substantially little or no paraffin remains between the outer periphery of the cover-flange and the outer flange of the jar. Resultantly a glass cover can be pried off the jar to provide access to the paraffin seal without danger of breakage.

The invention is not to be understood as restricted to the precise details of construction set forth, but may be modified by the skilled mechanic without departing from the spirit and scope of the invention.

Having thus described the invention, what I claim as new, and desire to secure by Letters Patent, is—

1. The combination with a jar provided with a channel, a cover extended into said channel, and sealing material within the neck of the jar and between the cover and the jar.

2. The combination of a jar having a channel at its upper end, a cover having a rim or flange extending into said channel, and sealing material such as paraffin, said channel being of sufficient capacity to contain a charge of said material which will pass into the jar and form an inner seal or wafer for the mouth of the jar.

3. The combination of a jar having a channel at its upper end, a cover having a rim or flange extending into said channel, and sealing material such as paraffin, said channel being formed of sufficient capacity to contain a charge of said material which will pass into the jar and form an inner seal or wafer for the mouth of the jar and whereby a seal will be formed between the cover-flange and jar-neck.

4. The combination with a jar having a reduced neck and an outer flange wherethen a channel is formed, a cover having a flange or rim extending into said channel, and seal-

ing material within the neck of the jar and between said flange or rim and said neck.

5. The combination with a jar provided with a channel, a cover extended into said channel, and sealing material within the neck 45 of the jar and between the cover and the jar, said jar being formed with a spout for directing the sealing material into said channel.

6. The combination with a jar provided with a channel at its upper end, a cover having a rim or flange extending into said channel and sealing material such as paraffin in the mouth of the jar and between the cover-flange and the neck of the jar, there being substantially no sealing material between the 55 outer periphery of the cover-flange and the outer wall of the channel.

7. The combination with a jar provided with a neck and an outer flange wherethen a channel is formed, a cover having a rim or flange extended into said channel, and sealing material within the neck of the jar and between said flange or rim, the top of said neck being higher than the outer flange of the jar.

8. The combination with a jar having a channel at its upper end, a cover having a rim or flange extending into said channel, sealing material such as paraffin forming an inner seal or wafer in the mouth of the jar, a 70 space being formed between the neck of the jar and the cover-flange and whereby the sealing material will pass therebetween and form a seal between the jar and the cover, and means for centralizing the cover around 75 the jar-neck.

HENRY D. STRONG.
